BURNER CONTROL SYSTEM

Carl G. Krommiller, Minneapolis, Minn., assignor
to Minneapolis-Honeywell Regulator Company,
Minneapolis, Minn., a corporation of Delaware

Application July 3, 1936, Serial No. 88,781

14 Claims. (Cl. 158—28)

My invention relates to a burner control system and more particularly to control apparatus for use in connection with fluid fuel burners.

The invention is particularly concerned with a new and novel fluid fuel controlling means which is designed to control the flow of fluid fuel to both a main fuel burner and to a pilot burner and at the same time to regulate the admission of air to said burners.

One of the objects of the present invention is to provide for use in a fluid fuel burner control system a fluid flow controlling device and a novel operating means therefor which is particularly adapted to operate said fluid flow controlling device slowly from closed to open position to avoid too rapid admission of fuel to the burner.

A further object of the invention is to provide in a burner control system a valve in control of the flow of fuel to the burner, a second valve in control of the flow of fuel to the pilot burner, and an air damper for controlling the admission of air to the burners, all of which are operated in a definite sequence by a single motor means.

A further object of the present invention is to provide a burner control system having a main burner and a pilot burner with a main valve and a pilot valve, respectively, controlling said burners in which a motor is provided for operating the two valves, which motor is connected to the main valve through a lost motion connection and in which the pilot valve is actuated by the motor while taking up the lost motion between the motor and the main valve.

A further object of the present invention is to provide a new and novel electrically operated motorized fluid flow control member wherein the motor is provided with two field windings of different strength and wherein a new and novel method is employed for controlling the energization of these field windings through a thermostatic or other control switch and through a further switching apparatus operated by the motor.

A further object of the present invention is to provide in a motorized valve a double valve disk construction wherein a smaller valve disk is moved from its seat first and relieves the fluid pressure on the larger of the two valve disks.

A further object of the present invention is to provide a new and novel arrangement in a mechanism having a movable element biased in one direction by a spring and operated in a different direction by a motor in which a shaft is employed to transmit the motion imparted by the motor or spring to the element to be moved and in which a novel means is employed to prevent the

thrust arising by the opposed actions of the spring and motor from being transmitted to said shaft.

A further object of the present invention is to provide a motorized valve of the type wherein a valve is moved to one position by a spring and to a different position by a motor in opposition to the spring in which means is provided for adjusting the travel of the valve without varying the amount of compression of the spring necessary to effect such travel.

Further objects of this invention will be apparent from the accompanying specification, claims and drawings, of which:

Figure 1 is an elevational view, partly in section, of my improved valve; 15

Figure 2 is a view of a portion of the operating mechanism of my valve taken in the opposite direction from Figure 1;

Figure 3 is a section taken along the line 3—3 of Figure 1;

Figure 4 is an elevational view of the motor mechanism looking in the direction of the arrows adjacent line 4—4 of Figure 1 and with the motor housing in section along said line; 25

Figure 5 is a plan view of the motor mechanism with the covering of the housing removed;

Figure 6 is a section along the line 6—6 of Figure 5;

Figure 7 is a sectional view along line 7—7 of Figure 5;

Figure 11 is an end view of the motor mechanism showing particularly the manual latching mechanism associated therewith; 40

Figure 12 is a view of the manual latching mechanism viewed from the opposite direction from which Figure 11 is viewed;

Figure 13 is a schematic view of a new and novel burner control system employing my improved valve; 45

Figure 14 is a view of a portion of the lever mechanism of a modification of my preferred species;

Figure 15 is a sectional view taken along the line 15—15 of Figure 14;

Figure 16 is a view of a modified form of pilot valve and the operating mechanism thereof; 55

Figure 17 is a view taken in section along the line 17-17 of Figure 16, and

Figure 18 is a sectional view taken along the line 18-18 of Figure 16.

5 Referring to Figure 1 of the drawings, the valve body proper is designated by the reference numeral 10. The valve body is provided with the usual inlet 11 and outlet 12. Extending across the interior of the valve body is a trans-
10 verse partition wall 9 which is provided with an opening therein to furnish a valve seat 13. A main valve disk 14 is adapted to seat on the valve seat 13. Mounted in said valve disk is an annular member 15 of suitable valve facing ma-
15 terial. The valve disk is further provided with a downwardly extending, threaded, tubular ex-
tension 16 and threaded onto this extension is a valve guide member 17. The valve guide mem-
ber comprises a body portion 18 which is provided
20 with a plurality of apertures 19 to permit pas-
sage of fluid therethrough. The guide 17 is further provided with elongated spaced guide
members 20.

The upper portion of valve disk 15 is provided
25 with a raised annular portion 22 forming a seat upon which a second valve disk 23 is adapted to seat. This valve disk is likewise provided with an annular member 24 of suitable valve facing ma-
terial. The valve disk 23 is further provided
30 with a screw threaded downwardly extending portion 25 on the exterior of which is threaded a guide member 26. This guide member is adapted to guide the movement of valve disk 23 by engaging the walls of the aperture 29 of valve
35 disk 14. A cap screw 30 is also threaded into the downwardly extending portion 25 of valve disk 23 and the head of this screw serves to limit movement of valve disk 23 away from valve disk 14. On the upper portion of valve disk 23 an
40 upstanding curved flanged member 32 is pro-
vided. This member is open at one side so as to slidably receive a stem 34 which is provided with a head portion 36 adapted to engage under the flange of member 32.

45 Stem 34 is provided at its upper end with two spaced annular collars 40 and 41. As more clearly shown in Figure 2, these two collars, 40 and 41, receive between them inwardly extending pins 43 of a lever 44 having a bifurcated portion 45, in the legs of which, the pins 43 are secured.
50 As shown more clearly in Figure 3, lever 44 is secured to a shaft 47 through a hexagonal por-
tion 48 on said shaft which is adapted to extend through a similar hexagonal opening in an en-
larged head 49 of lever 44. It will be seen that
55 rotation of shaft 47 causes a resulting rotation of lever 44 which in turn causes movement of valve stem 34. When this rotation of shaft 47 is in a direction to cause upward movement of
60 valve stem 34, the valve disk 23 will first be raised until the head of cap screw 30 engages the lower portion of extension 16 of valve disk 14, where-
upon further movement of valve stem 34 is effec-
tive to lift the main valve disk 14 off of its seat.
65 In view of the fact that valve disk 14 has a central aperture 29 therethrough which com-
municates with apertures 19 in the valve guide
member 17, a movement of valve disk 23 away
from seat 22 permits the fluid pressure on top
70 of valve disk 14 to be relieved so that the large
valve disk 14 can then be readily lifted away
from its seat.

Secured to the top of valve body 10 is a cap member 50. This cap member is secured to valve body 10 through any suitable adapter member 51.

This adapter member may be of any type which permits a standard valve head member to be at-
tached to various sizes of valve bodies. As shown
most clearly in Figures 2 and 3, the valve cap 50
is provided with a plurality of upstanding studs 5
53 which serve to support a base plate 54 on which
the motor mechanism 55 is mounted. Base plate
54 is secured to studs 53 through any suitable
fastening means, such as machine screws 56 at-
tached to the underside of valve cap 50. In the
10 interior thereof is a valve guide member 58 which
member serves to guide valve stem 34.

A means for sealing shaft 47 is shown most clearly in Figure 3. Extending into opposite sides of the valve cap 50 are sleeve members 59 15 and 60. These sleeve members 59 and 60 are threaded into the interior cap member 50 and serve to house bearing members 61 and 62. At its innermost end, sleeve 60 is provided with an enlarged annular shoulder in which is mounted an annular member 63 of packing material. This packing material 63 is adapted to be en-
gaged by a shoulder 64 on shaft 47. In the outermost portion of sleeve member 59 is a spring 66 which bears against a movable pin 67 which in turn is in abutting engagement with shaft 47. The action of spring 66 is accordingly to move shaft 47 to the right and to urge shoulder 64 into engagement with packing material 63, thus serving to seal the shaft against the escape of fluid. As a further sealing means, sleeve 60 is provided at its outer end with an internal annular recess filled with packing 69 which is held in position by a gland nut 70. Inasmuch as escape of fluid from the interior of valve cap 50 adja-
35 cent sleeve members 59 and 60 is prevented by reason of the threaded connection and packing washers 11 and 12 which are clamped between the sleeve members and the valve cap and by reason of the sealing means just described com-
40 prising shoulder 64 and packing 63, shaft 47 is effectively sealed against the escape of fluid while at the same time free rotation of the shaft is permitted.

The means for transmitting rotation to the shaft 47 will now be described. It will be noted from Figures 1 and 2 that the outermost end of shaft 47 is provided with a square end. Mounted on this square end is a lever 75 which may be of any desired construction. As best shown in Figure 10, this lever has a reversely bent portion 76 to provide two spaced arms 77 and 78 which engage the shaft at spaced points. The reversely bent portion 76 is provided with a slot 79 as best shown in Figure 1, and extending between arms 77 and 78 is a bolt 79 which upon being tightened serves to clamp lever 75 securely to shaft 47. Lever 75 is connected at its outer end to a bell crank lever 86 through a cap screw 81. Bell crank lever 86 is provided with a hub portion 8 which is mounted upon a bearing constituted by the outer annular extension 89 of sleeve member 60. Pivotally connected to one arm 90 of the bell crank lever 86 is a rod 91. This rod 91 extends into a spring housing 92 and is pro-
55 vided at its outermost end with a collar member 93 which is engaged by a spring 94. Collar member 93 is held in position on rod 91 by a nut 95 which can be employed to adjust the ten-
60 sion of spring 94. Through the action of spring 94 on rod 91 and accordingly on arm 90, the bell crank lever 86 is urged in a clockwise direction looking in the direction from which Figure 1 is viewed. Connected to the other arm 96 of the bell crank lever 86 is a link 97 which is designed 65 70 75

to be actuated by a motor so as to move bell crank lever 86 in a counter-clockwise direction against the action of spring 94. It will be noted that lever 75 is not directly acted on by the spring 94 or the motor. The only force applied to the lever 75 is that necessary to counteract the weight of the valve. The relatively large moment caused by the opposing actions of spring 94 and the motor is entirely applied to lever 86. The result is that the relatively slender shaft 47 upon which lever 75 is mounted is subjected only to a comparatively small side thrust, the greater part of the side thrust being applied to the large bearing member 89. Link 87 is secured at its upper end to a lever member 99 which is provided with a shoulder 100 adapted to be engaged by a pin 101 of a crank arm member 102 which is driven by the motor. The structure of members 99 and 102 and the operation thereof will be explained in greater detail in a subsequent paragraph.

Referring to Figure 4, I have shown the motor mechanism of my valve with a casing 105 therefor shown in section along the line 4-4 of Figure 1. Referring to Figure 4, the motor proper is designated by the reference numeral 106. The particular structural details of this motor are of no importance as far as the present invention is concerned although the motor is provided with two field windings of different size, as is common in the motor art, with certain types of motors and as will be explained in greater detail in subsequent paragraphs. The motor is provided with a motor shaft and has secured at the outer end a pinion 107 which drives through a suitable reduction gearing 108, a shaft 109. The gear at the low speed end of reduction gearing 108 is designated by the reference numeral 110. The reduction gearing is designed to provide a very large reduction in speed between its high speed and low speed ends. This is for the purpose of causing the valve to be moved slowly from closed to open position. This is a highly important feature where the valve controls the flow of fuel to a very large burner. If the fuel is not admitted gradually, there is danger of a large amount of fuel being admitted to the burner, before the burner is completely ignited, often causing an explosion.

Three spaced upstanding bracket members 111, 112, and 113 are provided for mounting the motor 106, the reduction gear 108 and the shaft 109, as is more or less apparent from the drawings. Bracket member 111 is bifurcated at its upper end to provide two spaced portions 115 and 116. Portion 116 has secured thereto a bearing sleeve 118. Similar bearing sleeves 119 are secured in bracket members 112 and 113. The sleeves 118 and 119 serve to rotatably support shaft 109.

The uppermost portions of bracket 111 and 112 are bent at right angles and serve to support a plate of insulating material 123 which is shown most clearly in Figure 5. Mounted upon insulating plate 123 are a plurality of switch blades 124, 125 and 126. As shown in Figure 6, switch blade 125 is secured at one end to the insulating plate 123 and is provided at its other end with a contact member 127 which is adapted to engage with a contact member 128 rigidly mounted upon insulating plate 123. At its intermediate portion, switch blade 125 is bent downwardly to provide a cam follower 129 which cooperates with a cam 130. Cam 130 is nonrotatably secured to shaft 109. Cam 130 is provided with an arcuate recessed portion 131 which is

sufficiently recessed so that when the cam follower 129 is in engagement with this portion, contacts 127 and 128 are in engagement. It will readily be seen that upon a rotation of cam 130 in the direction of the arrow in Figure 6, which direction is the direction in which the cam moves during valve opening movement, contacts 127, and 128 will first be separated and then moved into engagement for a portion of the movement of cam 130 and then moved out of engagement. Upon a reverse movement of cam 130, the same action will take place. The function of switch blade 125 and its associated contacts 127 and 128 is to cause a successive energization and de-energization of the lifting coil of the motor during valve opening movement as will be explained in more detail in subsequent paragraphs.

Referring to Figures 5 and 7 and more particularly to the latter, it will be noted that switch blade 124 is secured at one end to insulating plate 123 and is provided at the other end with a contact 134 which is adapted to engage with a fixed contact 135 on the insulating plate 123. Similarly, switch member 126 is also provided with a depressed portion 136 which serves as a cam follower and cooperates with a cam member 137. Cam member 137 is provided with square shoulder portions 138 and 139 which engage with the sides of the opening in insulating plate 123 and serve to limit the movement of cam 137 in opposite directions. Referring again to Figure 4, it will be noted that cam member 137 is located adjacent a collar 120 which is rigidly secured to shaft 109. Located between the cam 137 and the collar 120 is a disk 140 of material having a comparatively high coefficient of friction. A spring 121 is located on shaft 109 and serves to urge cam 137 against the friction disk 140. Cam 137 is not rigidly secured to shaft 109 and is restrained from free rotation thereon only by being urged against friction disk 140 by spring 121. It will thus be apparent that upon initial rotation of cam 137 in the direction of the arrow in Figure 7, which arrow likewise designates the direction taken by cam 137 during valve opening movement, the cam 137 will first be moved so that cam follower 136 is permitted to move into a recessed portion 141 of the cam, whereupon the shoulder 138 will engage the left wall of the opening in insulating plate 123 and prevent further movement of the cam. Continued rotation of the shaft 109 after this occurs merely results in cam 137 slipping on the shaft 109. As soon as shaft 109 is rotated in the opposite direction, cam follower 136 will move back up onto the raised portion adjacent the depression 141 and the parts will assume the position shown in Figure 7. Continued rotation of the shaft after this occurs again results merely in the cam slipping on the shaft. It will thus be seen that the operation of switch blade 124 and cam 137 is to cause an immediate closing of contacts 134 and 135 upon rotation of the shaft in one direction and in immediate separation of these contacts upon rotation of the shaft in the other direction regardless of the point at which such reverse rotation of shaft begins.

Secured at the outer end of shaft 109 is a sleeve member 145. This sleeve member 145 is secured in any desired manner, but as shown more particularly in Figure 8, the shaft 109 is provided with a square end over which sleeve member 145 extends. A screw 147 serves to secure the sleeve to the shaft 109. Nonrotatably secured at the outer end of sleeve 145 is crank disk 102 and

rotatably secured between crank disk 102 and shoulder portion 148 on sleeve 145 is lever 99. Referring again to Figure 1, it will be noted that member 102 is provided with a pin 101, which, upon rotation of crank disk 102 in a counter-clockwise direction, is adapted to engage with the shoulder portion 100 of lever 99. By reason of this construction, a one-way connection between the motor and the valve is obtained, the importance of which will be more apparent from subsequent paragraphs.

At the end of shaft 109 opposite to that on which sleeve 145 is secured, a pair of cams 152 and 153 are non-rotatably secured as shown in Figure 2. Cam member 152 is designed to actuate a damper arm 154 and cam 153 to actuate a flare pilot valve 155. Damper arm 154 is pivotally secured to the motor housing 105 by means of a suitable member 150. On one side of the pivot point 150, the damper arm is provided with a weight 151 and on the other side thereof, it is provided with a follower pin 162 which is adapted to move along the cam surface of cam 152. It will be readily seen that upon rotation of shaft 109 in the direction of the arrow of Figure 2, the cam follower pin 162 rides up on the toe portion 163 of cam 152 causing the left end of lever 154 to move downwardly against the action of weight 151. Damper arm 154 is employed to actuate a secondary air damper as will be more apparent from a subsequent description of the operation of the valve.

The flare pilot valve 155 comprises a housing 156 which is secured through any suitable fastening means 149 to the side of the valve cap 50. The valve body 156 is provided with a vertically extending passage 157 which has extending across it adjacent its mid point an apertured partition 158. This partition 158 serves to provide a valve seat upon which a valve head 159 is adapted to seat. Secured in the lower end of the valve body 156 is a plug member 160 which has a recessed portion in which is mounted a spring 161. Spring 161 bears against the valve head 159 so as to urge it to closed position. Threadedly secured in the upper end of the pilot valve housing 156 is a sleeve member 164 which is provided at its lowermost portion with an annular extension 165. This extension serves a joint function of guiding the valve stem 166 attached to valve head 159 and of engaging valve head 159 to limit its closing movement. It will be seen that by screwing sleeve 164 in or out, the closing movement of the valve may be limited to any desired extent. A lock nut 167 is provided for the purpose of locking a sleeve 164 in any adjusted position. Secured in the upper end of sleeve 164 is an annular guide member 168 which serves to further guide the movement of valve stem 166. Located within sleeve 164 is a suitable packing material 170 which is urged in sealing engagement with shaft 166 through a spring 171 which bears at one end against guide member 168. The pilot valve housing is provided with a transversely extending passage 172 which communicates with a lower portion of chamber 157 and is in further communication with a passage 173 extending through the valve housing cap 50. Gas is permitted to enter the lower portion of chamber 157 through passages 173 and 172 from the interior of the main valve housing. A pipe 174 communicates with the upper portion of chamber 157 on the opposite side of valve 155.

An elongated rod-like member 175 is slidably supported in a bracket 176 attached to the side

of the motor housing 105. At its lower end, member 175 is provided with a conical portion 177 which is adapted to engage the upper end of valve stem 166. At its upper end, member 175 is provided with a roller 178 which functions as a cam follower and bears upon the cam surface of cam 153. It will be noted that cam 153 is provided with a toe portion 179 of limited extent so that upon continued rotation of cam 153 in the direction of the arrow of Figure 2, the cam will be effective to move member 175 to depress valve stem 166 for a short period of time and then to permit the same to move upwardly again by reason of the biasing action of spring 161. Since this valve is used to control the flow of gas to the pilot burner, this action of the cam will be effective to cause the normal flow of gas to the pilot, as determined by the extent to which valve 159 is held away from its seat by annular extension 165, to be momentarily increased so as to flare the pilot outwardly. Cam 153 is so located with relation to the opening movement of the valve that this flaring action takes place during the initial opening of the main valve.

Referring to Figure 4, it will be noted that one of the gears of the gear train 108, which gear is designated by the reference numeral 180, is mounted on an elongated shaft 181 which terminates in a squared portion 182. As is shown in Figure 2, this squared portion 182 is located adjacent an opening 183 in the motor housing 105 so as to permit the application of any suitable crank or key member to squared shaft 182. By the application of such a key or crank member to shaft 182, the gear train may be manually rotated in the event of power failure. This causes the valve to be manually operated in a manner to be more fully described later.

Referring to Figures 11 and 12, there is shown a means for latching the valve in open position when manually opened and for insuring that the valve is returned to the control of the motor upon restoration of power. In Figure 11, the gear train is shown in an end view. Attached to the end gear 110 of the low speed end of the gear train 108 is a pin 184. This pin 184 serves a double function during the normal operation of the valve by the motor. Pin 184 serves to limit the opening movement of the motor by engaging a stop pin 185 which is secured in bracket 113. When the valve is manually operated, pin 184 cooperates with a latching member 186 to hold the valve in open position. Latching member 186 is pivotally mounted to an upstanding bracket 187, as shown more clearly in Figure 12. This bracket 187 is secured to bracket 113 as indicated in Figures 4, 11 and 12. Latching member 186 is provided with an upstanding shoulder portion 188 and bracket 187 is similarly provided with such a shoulder portion 189. A coil spring 190 is located upon a pin 191 which serves to pivotally connect latching member 186 to bracket 187 and the ends of the spring bear against the respective shoulder members 188 and 189 serving to urge member 186 into the position shown in Figure 11. A pin 192 is located on bracket 113 and limits the outward movement of latching member 186 by engaging with an extension 193. This extension 193 is curved so as to be able to securely engage with pin 184. When the valve is manually raised and it is desired to latch the valve in open position, latching member 186 is moved inwardly by pulling down upon a handle portion 195 thereof, so as to bring the curved surface of extension 193 into the path of the

return movement of pin 184. This position, looking in the direction opposite to that from which Figure 11 is viewed, is shown in Figure 12. It will be seen that the latching member 186 through the engagement of extension 193 with pin 184 is effective to prevent the return rotation of gear 110. Moreover, by reason of the curved surface of extension 193 engaging with the curved surface of pin 184, latching member 186 is held in its locked position when released due to the fact that pin 184 is urged against the curved surface of extension 193 and thus locks latch 186 in the position shown.

The operation of moving the latch inwardly has a further effect which will now be described. Referring to Figures 4, 5 and 12; it will be noted that latching member 186 is provided with a projecting stud 197 of insulating material which is adapted to be moved downwardly when latching member 186 is moved into latching position. The spring blade 126, which was previously referred to as mounted upon plate 128, has one end located in the path of movement of stud 197. This spring blade 126 has a contact 199 secured thereto which contact is adapted to be moved into engagement with a stationary contact 200 upon base 123. As will be apparent from Figure 4, downward movement of insulating stud 197, such as occurs upon a moving of latching member 186 into latching position, causes spring blade 126 to be moved downwardly and to effect the engagement of contacts 199 and 200. The engagement of these contacts will result in the closing of a circuit to the motor independent of the normal control means as will be apparent from the description of the operation in a subsequent paragraph.

In Figure 13, I have disclosed a schematic view of a burner system employing my improved valve. In this figure, the valve is shown in a highly schematic form for the purpose of more clearly understanding the action thereof. Inasmuch as the elements of the valve are designated by the same reference numerals as employed in connection with the previous description of the valve, it is unnecessary to specifically describe these elements again in connection with this valve.

Referring to said figure, a main gas burner 210 is shown as located within any suitable furnace 211. Gas is supplied to the main burner 210 through a pipe 212 which communicates with gas supply pipe 213, the communication of which is controlled by the valve of the present invention. A pilot burner is designated by the reference numeral 214 and is supplied with fuel through pipes 215 and 216, the communication of which pipes is controlled by the flare pilot valve 155. Pipe 216 leads to the gas supply pipe 213 and is connected thereto independently of the main valve 10. This pipe corresponds to the passage in the valve mechanism provided by the interior of valve housing 10 and by passage 173. The admission of secondary air to the gas burner is controlled by a secondary air damper 218 which is pivoted to the furnace casing at 219 and is adapted to open downwardly by the action of gravity when permitted. A flexible connecting means, such as a chain, is indicated by the reference numeral 220 and is employed to connect the damper 218 with damper arm 154.

As previously explained, the motor 106 is conventional with the exception that it is provided with two field windings, one of substantially greater size than the other. Referring to Fig-

ure 13, the rotor of the motor is designated by the reference numeral 225. Associated with said rotor is a low torque field winding 226 and a high torque field winding 227. The low torque field winding 226 serves as a holding coil and the high torque field winding 227 as a lifting coil.

Power is supplied for operation of this system through a step-down transformer 230. This transformer comprises a line voltage primary 231 which is connected to line wires 232 and 233 leading to a suitable source of power (not shown). The step-down transformer comprises in addition a core 234 and a low voltage secondary 235.

A control switch is generally designated by the reference numeral 240. This control switch may take any desired form but in the present instance is shown as a thermostatic switch comprising a bimetallic element 241 to which is attached a contact arm 242. Secured to the contact arm 242 are contacts 243 and 244 which are adapted to be moved into engagement with fixed contacts 245 and 246, respectively. As will be noted from the drawings, contacts 243 and 245 are more widely spaced than contacts 244 and 246. The bimetallic element 241 is so arranged with respect to the contact arm 242 that upon a decrease in temperature the contact arm is moved in the direction of the stationary contacts 245 and 246. When such a drop in temperature occurs, contacts 244 and 246 will first be moved into engagement by reason of their closer spacing and upon a further drop in temperature, contacts 243 and 245 will be moved into engagement.

Operation

The various elements in Figure 13 are shown in the position which they assume when the temperature to which thermostatic switch 240 responds is at or above the desired value. Under such conditions, the main valve 10 is closed, the pilot valve 155 is in its minimum flow position and the secondary air damper 218 is closed. In this connection, it may be stated that the various elements are also shown in Figures 1 to 11 in this position so that with the single exception of Figure 12, all the elements are shown in valve closed position.

Assuming now that the temperature falls below the value for which the thermostatic switch 240 is maintained, engagement will first be effected of contacts 244 and 246. The engagement of these contacts will not, however, cause the establishment of any energizing circuit. If the drop in temperature continues a predetermined amount, engagement of contacts 243 and 245 will also be effected. Upon this occurring, the following energizing circuit for the low torque field winding or holding coil 226 is established; from the right hand terminal of secondary 235 through conductor 250, contacts 246 and 244, contact arm 242, contacts 243 and 245, conductors 251 and 252, holding coil 226, conductor 253, and conductor 254 to the other terminal of secondary 235. This will cause the energization of field winding 226 which though not exerting sufficient torque to raise the valve does exert sufficient torque to rotate the motor up till the time that pin 101 moves into engagement with shoulder 100 of lever 98. Due to the fact that during valve closing movement, the motor and gear train have considerable momentum and continue to run backwards after the valve has reached its seat, crank disk 102 will be in a position such that pin 101 is considerably spaced from shoulder 100, thus permitting a substantial amount of rotation of shaft 109 by the motor 106 before

engagement of pin 101 and shoulder 100 is effected.

The initial rotation of shaft 109 is effective to permit the cam follower 136 of the switch arm 124 to move downwardly into the recessed portion 141 of cam 131 so as to effect engagement of contacts 134 and 135. When this takes place, the following holding circuit is established for field winding 226: from the right hand terminal 10 of secondary 235 through conductor 250, contacts 246 and 244, contact arm 242, bimetallic element 241, conductor 255, contacts 135 and 134, switch arm 124, conductor 252, field winding 226 and conductors 253 and 254 to the other terminal 15 of secondary 235. It will be noted that the holding circuit just traced is independent of contacts 243 and 245. Thus if the temperature momentarily rises slightly so as to cause disengagement of contacts 243 and 245 without causing disengagement 20 of contacts 244 and 246, the field winding will remain energized. In this manner I guard against the periodic energization and deenergization of the field winding such as would occur with a slight but rapid fluctuation in temperature.

Immediately after the engagement of contacts 134 and 135, the cam follower 129 of switch blade 125 moves down onto the recessed portion 131 of the cam surface of cam 130 permitting the engagement of contacts 127 and 128. As soon as this takes place the following circuit is established for the lifting coil 221: from the right hand terminal of secondary 235 through conductor 250, contacts 246 and 244, contact arm 242, bimetallic element 241, conductor 255, contacts 135 and 134, switch arm 124, conductors 251, 258 and 259, switch arm 125, contacts 127 and 128, conductor 260, lifting coil 221, conductor 261, and conductor 254 to the other terminal of secondary 235. It will be noted that the closing 30 of contacts 127 and 128 in effect connects field winding 221 in parallel with field winding 226 between the junction of conductors 257 and 258 and the junction of conductors 261 and 253. It will be noted that the lifting coil 221 was not connected into the circuit until after the establishment of the holding circuit by reason of the engagement of contacts 134 and 135. This is highly desirable due to the fact that until the holding circuit is established, the energization of the field windings is somewhat uncertain due to the 40 possibility of immediate separation of thermostat contacts 243 and 245. Since the field winding 221 takes considerable more current than field winding 236, it is desirable that winding 221 be not connected into the circuit until the holding circuit has been established with the result that the circuit will remain established.

With both the lifting and holding coils 221 and 226 energized, it is possible for the valve 10 to be opened. The motor is now effective to 50 rotate shaft 109 causing the pin 101 to move into engagement with the shoulder 100 causing lever 99 to move in the direction of the arrow of Figure 1. This causes an upward movement 55 to be imparted to link 97 which in turn causes a counter-clockwise rotation of bell crank 86 against the action of spring 94. This counter-clockwise rotation of bell crank 86 is imparted to lever 75 which in turn causes a similar rotation of shaft 41. As previously explained, this 60 counter-clockwise rotation of shaft 41 is effective to lift the valve stem 34 causing the valve disk 23 to first be lifted off of its seat on large valve disk 14 relieving the pressure on the large disk 70 75 and then to lift the large valve disk 14 opening

the valve 10. This permits a flow of gas to the main burner 210.

It will be noted in Figure 1 that the angle between lever 99 and link 97 in the position assumed when the valve is closed is slightly greater than 90°. Similarly, the angle between link 97 and arm 96 of lever 86 is slightly less than 90°. Likewise, the angle between arm 90 of lever 86 and rod 91 is slightly greater than 90°. The result is that after an extremely small amount of movement of these elements in valve opening direction, they are all disposed perpendicularly to each other and the spring is operating against the motor through a maximum moment arm. As the valve moves farther to open position, this moment arm decreases. This decrease in moment arm is accompanied by an increase in the force exerted by the spring 94 as it becomes more compressed. The result is that the moment exerted by spring 94 tending to close the valve remains substantially constant, thus maintaining a uniform load on the motor. This is especially important in a slow opening valve wherein the spring must be quite powerful in order to rotate the rather long gear train employed. If no arrangement is provided for maintaining the moment exerted by the spring comparatively constant, the motor must be of an excessively large size to overcome both the friction of the gear train and the force of the spring during the final portion of the opening movement of the valve.

Before the main valve is opened and even before pin 101 has engaged shoulder 100, the toe portion 179 of cam 153 has engaged the end of member 175 depressing the valve head 159 of pilot valve 155, thus increasing the flow of gas to the pilot burner 214. The toe portion 179 of cam 153 extends sufficiently far to maintain the flame of the pilot burner 214 extended until the main valve 10 has opened appreciably. The result is that while gas is being first admitted to the main burner 210, the pilot flame is extended so as to facilitate the ignition of the main burner. Before the valve 10 has reached full open position, however, member 175 has ridden off of the other side of the toe portion 179 so as to again permit valve 159 to assume a position of minimum flow. While in the previous description, the sleeve 164 of flare pilot valve 50 155 is so adjusted as to constantly maintain a minimum flow of gas through the flare pilot valve, it is wholly possible, if some means is provided for igniting the pilot, to have this adjusted so that the flare pilot valve is entirely closed and is opened upon the valve being opened. While I have shown for purpose of illustration the valve as employed in connection with the type of system wherein the pilot is constantly burning when the main valve is closed and is flared when it is 60 desired to ignite the main burner, it is to be understood that my structure is not limited to this use in any manner whatsoever and that it is just as adaptable for use in the type of system wherein the pilot is intermittently operated.

At the same time that the main valve is being opened and simultaneously with the initial opening of flare pilot valve 159, the follower pin 162 attached to damper arm 154 engages the toe portion of cam 152 causing the left hand end of 70 damper arm 154 to move downwardly permitting the opening of secondary air damper 218. Thus before the main valve 10 is fully open, the secondary air damper 218 is moved to open position so as to permit air to flow to the burner 210.

While it is preferred to employ an inwardly opening secondary air damper, my damper actuating mechanism is adaptable for use with a secondary air damper which opens outwardly. 5 All that is necessary to do this is to reverse the connections of chain 220 and weight 151 to the damper arm, the position of weight 151 being adjusted in accordance with the weight of the secondary air damper. 10 Referring again to the opening of the main valve, the continued rotation of shaft 109 such as occurs during this opening process causes cam 130 to assume a position wherein cam follower 129 is again moved out of the recessed portion 15 131 so as to again cause separation of contacts 127 and 128. When this occurs, the previously traced circuit to lifting coil 227 is interrupted so that only the holding coil 226 remains energized. While the holding coil 226 exerts insufficient 20 torque to lift the valve, it is sufficient, due to the friction of the gear train, to hold the valve in open position. As previously explained, the opening motion of the gear train is stopped by reason of pin 184 engaging stop pin 185. The 25 holding coil is now effective to hold pin 184 in engagement with pin 185 and to thus hold the valve open. Due to the fact that the current consumption of the holding coil is relatively small, the heating caused by the continued 30 energization thereof is relatively small as compared with the heating which would result if only one large winding were employed for both lifting and holding. This is particularly important with a device of the type which is moved to its deenergized position by a spring since it is imperative that the bearings do not stick, as will often result if they are heated excessively by heat given off by the motor.

As soon as the temperature to which thermostat 240 is responsive has risen above the value 40 for which it is set so as to cause disengagement of contacts 244 and 246, all the circuits previously traced will be immediately interrupted so that the motor is completely deenergized. As soon as 45 this occurs, spring 94 acting through bell crank lever 86, is effective to return the valve to closed position. As the valve reaches closed position, the flare pilot valve 155 will again be moved open to cause a flaring of the pilot flame so as to insure that the diminished quantity of gas issuing 50 from burner 210 is completely burned. At the same time, cams 130 and 137 will be effective to assume the position shown in Figure 13 causing separation of not only switch contacts 127 and 128 but also contacts 134 and 135. Upon the 55 main valve reaching its seat, the motor and gear train have acquired sufficient momentum so that they continue to rotate. This continued rotation is possible by reason of the one-way connection afforded by pin 101 and shoulder 100 of lever 99. 60 By reason of this possibility of the continued rotation of motor and gear train, rebounding of the valve from its seat is prevented.

If it should happen that there is a power failure 65 and it is desired to open the valve, the same may be manually opened as previously explained. This may be done by inserting a crank such as crank 264 onto the square end 182 of shaft 181 and rotating the entire gear train, thus opening 70 the valve. When the valve reaches substantially open position, latching member 186 is moved inwardly by pulling down on handle 195, as previously explained, causing the curved shoulder of extension 193 to be moved into the return path 75 of pin 184. The crank is then released allowing

pin 184 to seat against this curved shoulder which retains the latch in its inner position.

As previously explained, the inward movement of latch 186 effects the engagement of contacts 199 and 200. The engagement of these contacts 5 is effective to cause energization of the field winding 226 through the following circuit as soon as power is restored: from the right hand terminal of secondary 235, through conductor 262, switch blade 126, contacts 199 and 200, conductors 256, 257 and 252, field winding 226 and conductors 253 and 254 to the other terminal of secondary 235. Because of the fact that the position of the curved shoulder of extension 193 permits sufficient return movement of gear 110 before pin 184 engages therewith, the cam follower 129 of switch arm 125 will be in the recessed portion 131 of cam 130 so as to effect engagement between contacts 127 and 128. Accordingly, upon restoration of power, the following circuit 20 is also completed to lifting coil 227: from the right hand terminal of secondary 235 through conductor 262, switch arm 126, contacts 199 and 200, conductor 259, switch arm 125, contacts 127 and 128, conductor 260, field winding 227, and 25 conductors 261 and 254 back to the other terminal of secondary 235. With both field windings 226 and 227 energized, the motor is able to rotate the shaft 109 against the action of spring 94 so as to cause a further opening of the valve. 30 This additional rotation of shaft 109 causes pin 184 to be moved away from engagement with the curved shoulder of extension 193 of latch 186, thus permitting latch 186 to be released and returned by reason of the biasing action of spring 35 190 to the position shown in Figure 11.

The movement of latch 186 back to its normal position causes switch arm 126 to effect a disengagement of contacts 199 and 200. If the thermostat 240 is now in a closed position calling for 40 the valve to be opened, the motor will remain energized and move the valve to full open position. If on the other hand, the thermostat contacts are separated indicating that the temperature is such as not to require the further maintenance of the valve in open position, the separation of contacts 199 and 200 will cause the motor to be deenergized so that the valve is returned to closed position. In this manner, I assure that if the valve is manually opened and latched in open 45 position, there is no danger of the same remaining out of control of the thermostat when power is restored. This is highly desirable inasmuch as the latching of the valve in open position and the inadvertently latching of the same in open position after restoration of power will defeat one of the very objects of the automatic control, that is, greater safety. 50

In Figures 14 and 15, there is disclosed a modification wherein means are provided for adjusting the movement of the valve without changing the action of any of the rest of the apparatus. In Figure 14, the elements which differ from those in the preferred form are shown in heavier lines than the rest of the structure. It will be noted that in lieu of the one vertically extending link 97 in the preferred species there are now two vertically extending links 297 and 298, both of which are connected to a lever 299 corresponding to lever 99 of the preferred species. Lever 297 is 60 identical in function to lever 97 of the preferred species and serves to connect lever 299 with an arm 296 of a bell crank 286. The link 298 is employed to connect lever 299 to lever 275 corresponding to lever 75 of the preferred species. 70 75

There is no connection between levers 275 and 296 as there is between the corresponding elements of the preferred species, and the actuation of lever 275, and consequently of the valve, is effected directly through link 298 rather than through the bell crank 296.

Means are provided for adjusting the connection of link 298 with lever 299. This adjustment is such that the position of lever 299 with respect to the pivot point is varied so as to decrease or increase the throw of the valve without affecting in any way the movement of lever 299 or of bell crank 296. Referring to Figure 15, it will be noted that lever 299 is substantially different in construction from lever 99 of the preferred species. Lever 299 comprises two strips 304 and 305, the former of which is pivotally mounted to a shaft 309 driven by the motor, which shaft corresponds to shaft 109 in the preferred species. These two strip members 304 and 305 are secured together at one end by means of a bolt 306 and at the other end by a bolt 307. In the latter case, a sleeve 308 surrounds the bolt 307 to prevent members 304 and 305 being drawn so closely together as to grip the lever 297 which is pivotally mounted on the sleeve 308. Located in the outermost strip member 305 is an arcuate slot 310 whose center of curvature coincides with the point of connection of link 298 with lever 275 when these two members are in closed position. A pin 311 extends through this slot. This pin is provided with a portion 312 of substantial diameter and a reduced shank portion 313. A shoulder is provided at the junction of these two portions, which shoulder engages one side of member 305 of lever 299. A nut 314 is threaded on the shank portion and serves to clamp pin 311 in position, serving to clamp the shoulder formed by the junction of portions 312 and 313 firmly against member 305 and serving to hold the same in any position in which it has been set.

The link 298 comprises a pair of eye bolts 315 and 316 adjustably connected through a turn-buckle 317 of any desired construction. The eye bolt 315 surrounds the portion 312 of pin 311 so as to form a pivotal connection between link 298 and lever 299. Due to the fact that the portion 312 of pin 311 has a length which is greater than the width of the eye portion of eye bolt 315, the eye bolt 315 remains freely pivotal with respect to pin 311 regardless of how tightly nut 314 is clamped. The other eye bolt 316 of link 298 is pivotally connected to lever 275.

It will thus be seen that means are provided for adjusting the radial position of the connection of link 298 with lever 299 and hence varying the throw of the valve. An important feature of the construction employed by me is that it is possible to adjust the movement of the valve for a given movement of the motor without in any way affecting the tensioning of the biasing means necessary to effect such movement. If in the preferred species the link 97 were merely made adjustably connectable with lever 99, the movement of the valve for a given movement of the motor could be varied but in so doing the tensioning of the spring 94 that would be necessary to effect such movement would likewise be varied. This is highly undesirable inasmuch as in some cases the spring would be very strongly compressed and in other cases only slightly compressed. If the apparatus were adjusted to function satisfactorily for one tensioning of the spring, it would not function satisfactorily for a different tensioning

of the spring. This is due to the fact that the spring must be carefully adjusted so as to just have sufficient tension to return the valve with the proper amount of force without having so much tension as to prevent satisfactory operation of the valve by the motor. By the provision of the arrangement shown in Figures 14 and 15, it is possible to adjust the movement of the valve without in any way affecting the tensioning of the spring necessary to effect such movement. This is accomplished by reason of the fact that the spring acts on bell crank lever 296 and this lever moves through the same arc of movement regardless of the amount of movement imparted to the valve.

Another advantage of this construction is that due to the fact that the center of curvature of slot 310 is at the junction of link 216 and lever 275 when these members are in valve closed position, the throw of the valve can be varied without affecting the valve closed position of the operating mechanism. In certain prior constructions of a similar type, it was necessary to readjust the mechanism each time the throw of the valve was varied, to permit the valve to close properly.

While the feature of the operation of Figures 14 and 15 is applicable to any type of motorized valve or for that matter to various types of mechanisms broadly, it is of particular advantage where the motor is of the modulating type wherein the valve may be moved to and stalled in any mid-position. Such motors are well known to the art and as an example of one such motor which would be suitable for use in connection with a valve of this type, is the motor mechanism shown in the patent to Lewis L. Cunningham No. 2,029,465 of February 4, 1936. In the structure of this patent, the pin 57 and the gear 55 would correspond in function to the pin 301 and the lever 302 of the present structure. Another example of a motor structure suitable for use with this valve is the patent to Willis H. Gille No. 2,032,658 of March 3, 1936. In this patent the shaft 21 would correspond to the shaft 309, the arm 22 to the lever 302 of the present structure and spring 18 to the biasing spring of the instant structure. However, while the invention finds particular utility in connection with a modulating motor such as is disclosed in the two patents just mentioned, it is of broad general applicability, as previously stated, and is of utility in connection with a motor such as is disclosed in the preferred species where it is desirable to adjust the throw of the valve.

In Figures 16 to 18, I have disclosed a modification wherein the flare pilot valve is actuated from the bell crank lever and wherein the pilot valve remains fully open during the entire time that the burner is in operation. Referring to Figures 16 and 17, it will be noted that a rearwardly extending arm 330 is secured to a bell crank lever 331. This rearwardly extending arm 330 is preferably fastened by screws or other suitable fastening means 332 to a hub portion 333 of the bell crank lever 331, which hub portion corresponds to the hub portion 88 of bell crank lever 86 in my preferred species. The arm 330 is provided with a horizontally extending finger 335 which is designed to cooperate with the flare pilot 70 336 to actuate the same.

Referring to Figure 18 wherein the pilot valve 336 is shown in cross section, it will be noted that the pilot valve comprises a housing including a main body portion 337 into which is threaded a valve guide member 338. A valve seat 339 is in

communication with a pipe 342 and is adapted to have a valve head 341 seated thereon. When the valve is moved from its seat, communication is permitted between pipe 342 and a second pipe 343, one of which is intended to be led to the gas supply and the other of which is intended to be led to the pilot burner to supply gas to the same. A valve stem 344 is connected to the valve head 341 at one end and at its other end is secured to a block 345. The guide member 338 is provided with a threaded recessed extension 346 onto which is threaded a sleeve 347. The sleeve 347 serves to limit movement of block 345 and consequently of valve 341 in valve closing direction. By adjusting the sleeve 347 the amount which the valve is held open in its minimum flow position may be adjusted. A lock nut 348 is provided for securing sleeve 347 in any adjusted position. A spring 349 is located in the recessed portion of extension 346 and serves a dual function of urging block 345 outwardly and hence biasing the pilot valve to an open position and also of compressing packing 351 serving to effectively seal the valve stem 344.

Bearing against the lower end of block 345 is a pin 353 which has a conical head 354 extending into a conical recess 355 of block 345. The pin 353 extends through the horizontally extending portion 356 of the arm 330. A spring 358 is located between the conical head 354 and the portion 356 of arm 330 and serves to urge the conical head 354 away from member 335, providing a strain release connection between member 335 and block 345. A nut 360 is threaded onto the lower end of pin 353 and serves to limit the movement of head 354 away from member 335. It will be readily seen that upon a counter-clockwise movement of bell crank lever 331, the portion 356 of arm 330 will be moved downwardly. The downward movement of this portion will cause the downward movement of pin 353 permitting the biasing spring 349 to move block 345 and consequently valve head 341 down so as to open the pilot valve 336. Referring again to Figure 16, it will be noted that the lever 365 which is connected to bell crank lever 331 is slotted at 366 and that the pin 368 which serves to connect the lever 365 with bell crank lever 331 extends through this elongated slot 366 and is free to move up and down thereon. The provision of this pin and slot connection results in there being lost motion between the bell crank lever 331 and the lever 365. Thus upon a valve opening movement, bell crank lever 331 will move a slight distance in a counter-clockwise direction before causing any movement whatsoever of lever 365 and consequently of the main valve. This movement of bell crank lever 331 before the lost motion between the lever 331 and lever 365 is taken up is sufficient to move portion 356 of arm 330 downwardly sufficiently to cause the flare pilot valve 336 to be fully opened. In this manner, the flare pilot valve is moved to full open position before the gas is admitted to the main burner as in the preferred species.

While I have described my valve as employed in connection with the supply of fuel to a burner control system, it is to be understood that certain features thereof are broadly applicable to any fluid flow controlling element and in some cases even to any motor actuated element. Moreover, there are certain features of the burner control system in which my valve is incorporated which are of broad general utility regardless of whether the valve happens to be a motorized valve of the type shown in the drawings. Gener-

ally speaking, I have shown certain specific embodiments of my invention. It is to be understood that these are for purposes of illustration and that my invention is to be limited only by the scope of the appended claims.

I claim as my invention:

1. In combination, a valve, means biasing said valve to one position, a motor for moving said valve to a second position, a lost motion connection between said motor and said valve whereby movement of said motor does not cause immediate movement of said valve, said motor comprising a rotor and a plurality of field windings, one of which is adapted to exert a relatively small torque on said rotor when energized and the other of which is adapted to exert a relatively large torque when energized, a source of electrical energy, a control switch having a pair of contacts which tend to be insecurely engaged and operative upon engagement of said contacts to cause energization of said field winding of relatively small torque to cause an initial movement of said motor, and switching means operative upon such movement to first establish a circuit independent of said pair of contacts between said source of energy and said small torque field winding and to then include said large torque field winding in said circuit in parallel with said small torque field winding, said operation of said switching means being completed before the lost motion between said motor and said valve has been completely taken up.

2. In combination, condition changing means, a device controlling the condition changing means, a motor for operating said device, a lost motion connection between said motor and said device so that initial movement of said motor does not cause movement of said device, said motor comprising a rotor and a plurality of field windings, one of which is adapted to exert a relatively small torque on said rotor when energized and the other of which is adapted to exert a relatively large torque when energized, a source of electrical energy, a condition responsive switch having two sets of contacts sequentially engageable and disengageable upon changes in the controlling condition adapted upon closure of both sets of contacts to cause energization of the field winding of relatively small torque to effect an initial movement of said motor, and switching means operative upon such movement to establish a circuit independent of the first to be disengaged of said contacts between said source of energy and said large torque field winding.

3. In combination, condition changing means, a device controlling the condition changing means, a motor for operating said device, a lost motion connection between said motor and said device so that initial movement of said motor does not cause movement of said device, said motor comprising a rotor and a plurality of field windings, one of which is adapted to exert a relatively small torque on said rotor when energized and the other of which is adapted to exert a relatively large torque when energized, a source of electrical energy, a condition responsive switch having two sets of contacts sequentially engageable and disengageable upon changes in the controlling condition adapted upon closure of both sets of contacts to cause energization of the field winding of relatively small torque to effect an initial movement of said motor, and switching means operative upon such movement to first establish a circuit independent of the first to be disengaged of said contacts between said

source of energy and said small torque field winding and to then include in said circuit said large torque field winding in parallel with said small torque field winding.

5. In combination, a fluid flow controlling member, a tension spring biasing said member to one flow controlling position, a rotary electrical motor, connecting means between said motor and said fluid flow controlling member such that 5
10 operation of said motor moves said member to a second flow controlling position against the action of said spring, means for varying the movement of said member for a given movement of said motor without changing the amount of
15 tensioning of said spring necessary to accomplish said movement of said member.

5. In combination, a fluid flow controlling member, a rotary electrical motor, connecting means between said motor and said member effective upon operation of said motor to move said member from a first fluid controlling position to a second fluid controlling position, means including a tension spring acting on an element of said connecting means to constantly urge said member to said first position, and means for varying the movement of said member for a given movement of said motor without varying the amount of tensioning of the spring necessary to accomplish said movement of said member.

30. 6. In combination a fluid flow controlling member, a tension spring, a motor, a support, a shaft rotatably mounted in said support, operative connections between said shaft and said member to be actuated whereby rotation of said 35
40 shaft causes actuation of said member, a first lever driven by said motor, a second lever, a connection between said first lever and said second lever and between said second lever and said spring whereby said spring acts through said 45 second lever to urge said first lever in a direction opposite to that in which it is driven by said motor, and a connection between said first lever and said shaft whereby the movement of said first lever is transmitted to said fluid flow controlling member, said connection being adjustable to vary the amount of movement of said flow controlling member for the same movement of said first lever.

7. In a slow opening valve mechanism, a valve, 50 a relatively high speed motor, a reduction gear train having a large reduction ratio and having the high speed end thereof connected to said motor, a linkage mechanism connecting said valve to the low speed end of said gear train, so that upon energization of said motor, said valve is slowly moved to open position, yieldable means connected to said linkage so as to oppose the movement thereof in valve opening direction, said yieldable means being of sufficient strength 55
60 to be operative upon deenergization of the motor to rotate through said linkage said gear train and said motor in the opposite direction to close said valve, the elements of said linkage being so disposed relatively to said spring that the moment arm through which said spring opposes the opening movement of said valve decreases as the valve moves to open position.

8. In a slow opening valve mechanism, a valve, 70 a motor for moving said valve to open position, a reduction gearing having a large reduction ratio for connecting said motor to said valve, means for biasing said valve to closed position, said biasing means having sufficient force to move said valve to closed position and rotate said gear train and motor in valve closing direction upon de-

energization of said motor, a support, a shaft rotatably mounted in said support, operative connections between said shaft and said valve whereby rotation of said shaft causes actuation of said member, a lever which is connected at spaced points to said biasing means and through said reduction gearing to said motor, a bearing for said lever secured to said support concentrically with said shaft and of sufficient size to withstand the side thrust caused by the forces exerted by said biasing means and said motor and a connection between said lever and said shaft whereby movement of said lever is imparted to said shaft to cause actuation of said valve.

9. In a slow opening valve mechanism, a valve, 15 a motor for moving said valve to open position, a reduction gearing having a large reduction ratio for connecting said motor to said valve, means for biasing said valve to closed position, said biasing means having sufficient force to move said valve to closed position and rotate said gear train and motor in valve closing direction upon deenergization of said motor, a support, a shaft rotatably mounted in said support, operative connections between said shaft and said valve whereby rotation of said shaft causes actuation of said member, a bell crank lever one arm of which is connected to said biasing means and the other of which is connected to said motor, a bearing for said lever secured to said support concentrically with said shaft and of sufficient size to withstand the side thrust caused by the forces exerted by said biasing means and said motor and a connection between said lever and said shaft whereby movement of said lever is imparted to said shaft to cause actuation of said valve.

10. In combination, a fluid flow controlling member, a rotary electrical motor, means connecting said motor and said fluid flow controlling member whereby operation of said motor moves said member to one flow controlling position, adjusting means whereby the amount of movement of said member for a given movement of said motor may be varied, and means independent of the adjustment of the adjusting means for at all times exerting a substantially constant tension on said member, for biasing said member in a direction opposite to that in which it is moved by said motor.

11. In combination, a fluid flow controlling member, a rotary electrical motor, connecting means between said motor and said member effective upon operation of said motor to move said member from a first fluid controlling position to a second fluid controlling position, means for varying the movement of said member for a given movement of said motor, and means, including a tension spring, for at all times exerting a substantially constant tension on said member to urge said member to said first position, whereby the same tension will always be exerted on said valve regardless of the movement imparted thereto by said motor.

12. In combination, condition changing means, a device controlling the condition changing means, a motor for operating said device, a lost motion connection between said motor and said device so that initial movement of said motor does not cause movement of said device, said motor comprising a rotor and a plurality of field windings, one of said windings exerting sufficient torque when energized to cause rotation of said rotor before the lost motion is taken up but insufficient torque to cause rotation of the rotor after the lost motion has been taken up,

another winding creating sufficient torque so that when both windings are energized, the rotor is caused to rotate after the lost motion has been taken up, a source of electrical energy, a 5 condition responsive switch having two sets of contacts sequentially engageable and disengageable upon changes in the controlling condition operative upon closure of both sets of contacts to cause energization of said one field winding, and 10 switching means operative upon movement of the motor under the influence of said one field winding to establish a circuit, independent of the last of said contacts to be engaged, between said source of energy and said other field winding.

15 13. In combination, a burner, a main valve in control of the flow of fuel to said burner, a pilot burner, a pilot burner valve, a motor, reduction gearing driven by said motor, lever means connected to said main valve, means biasing said 20 main and pilot valves to closed positions, an operating member connected to said pilot valve, valve-actuating means driven by said reduction gearing, said means including a crank pin, means connected to said lever means located in the 25 path of movement of said pin, said means being so configurated and arranged with respect to said pin that upon engagement by said pin in response to rotation of said gearing by said motor in one direction, said means will be moved by said pin in a direction to cause the opening of the 30 main valve and will be retained in valve open position by said pin as long as the motor remains energized, the biasing means for the main valve being of sufficient strength that upon deenergization of said motor, said motor will be caused to run in a reverse direction by reason of the force 35 imparted to said pin, the momentum of said motor keeping the motor running long enough to carry the pin a substantial distance from the means connected to the lever means, whereby

upon energization of the motor, there will be considerable lost motion before the pin starts to open the main valve, and means for causing said pilot valve to be opened by said motor during the period that the lost motion is being taken up. 5

14. In combination, a burner, a main valve in control of the flow of fuel to said burner, a pilot burner, a pilot burner valve, a motor, reduction gearing driven by said motor, lever means connected to said main valve, means biasing said main and pilot valves to closed positions, an operating member connected to said pilot valve, valve actuating means driven by said reduction gearing, said means including a crank pin, means connected to said lever means located in the 15 path of movement of said pin, said means being so configurated and arranged with respect to said pin that upon engagement by said pin in response to rotation of said gearing by said motor in one direction, said means will be moved by 20 said pin in a direction to cause opening of the main valve and will be retained in valve open position by said pin as long as the gearing is under the control of said motor, the biasing means for the main valve being of sufficient 25 strength that said gearing will be caused to run in a reverse direction by reason of the force imparted to said pin, when the gearing is no longer under the control of said motor, the momentum of the gearing being sufficient to carry the pin a substantial distance from the means connected to the lever means, whereby upon energization of the motor, there will be considerable lost motion before the pin starts to open the main valve, and means responsive to the operation of the motor during the time that the lost motion is being taken up for causing said pilot valve to be opened against the action of the biasing means. 30
